UNITED STATES PATENT OFFICE.

ABRAM B. SPRINGSTEAD, OF KALAMAZOO, MICHIGAN.

HEAVIER-THAN-AIR FLYING-MACHINE.

1,037,353.

Specification of Letters Patent.

Patented Sept. 3, 1912.

Application filed September 5, 1911. Serial No. 647,755.

To all whom it may concern:

Be it known that I, ABRAM B. SPRINGSTEAD, a citizen of the United States, residing in the city and county of Kalamazoo, 5 State of Michigan, have invented certain new and useful Improvements in Heavier-Than-Air Flying-Machines, of which the following is a specification.

This invention relates to improvements in 10 heavier-than-air flying machines.

The objects of the invention are, first, to increase and improve the stability of flying machines. Second, to provide improved steering means for such machines. Third, 15 to provide improved means of controlling such heavier-than-air flying machines. Fourth, to provide improved means of collapsing such structures so that they will occupy the minimum space when not in the 20 air.

Further objects, and objects relating to details of operation and economies of construction will definitely appear from the detailed description to follow.

I accomplish the objects of my invention 25 by the devices and means described in the following specification.

The invention is clearly defined and pointed out in the claims.

A structure which is a preferred embodiment 30 of my invention is fully illustrated in the accompanying drawing, forming a part of this specification, in which:

Figure I is a perspective view of my improved flying machine as it appears when at 35 rest. Fig. II is an inverted plan view of the same. Fig. III is a front elevation view of the framework, the forwardly-projecting rudder device and stem structure being omitted, the position of the side wings, 40 when the machine is in flight, being indicated by dotted lines. Fig. IV is a detail elevation view in broken section of the adjusting device for the upper collapsible structure. Fig. V is a detail view of the 45 adjusting means for the rearward horizontal rudder.

In the drawing similar numerals of reference refer to similar parts throughout the 50 several views.

Considering the numbered parts of the drawing, the bottom rib or keel 1, extends longitudinally from stem to stern of the

main body and is provided with a framework above, something like that of a box 55 kite, the same being made up of lower frame bars 2-2 and upper frame bars 3-3, the box being disposed upon one corner and being provided with a transverse bar 4 bracing the same and serving as attaching 60 means for various parts. The said bar 4 extends at each side to carry side planes 10, as will hereafter appear.

Uprights 5-5 are at each side, both front and rear, the rear not being shown as they 65 are exactly back of the front. A cross bar 6 connects the said standards to the rib or keel 1. Caster wheels 7 are carried at the bottom and these caster wheels are connected together for steering purposes by 70 the transverse link bar 8 connected to a horizontal bell crank 9 secured to each front caster wheel at each end. These bell cranks are connected by cords or cables 21' to the 75 forward rudder.

Lower side planes 10 are secured to the cross bars 4 at each side, see particularly Figs. I and II. These are provided with wing extensions 10', which are hinged to the side planes on oblique lines converging 80 toward the rear of the machine, and projecting arms 11 extend up from the frame of these wing extensions to limit their upward movement. These wings are covered by canvas 12, and are provided with longitudinal diagonal braces 13. The side wing extensions 10' are free to drop downwardly, 85 except as they are acted upon by air currents or by the air when the machine is being propelled.

A cable 14 is connected to each wing and extends down to a guiding pulley 16, then upwardly to the pivoted pilot back lever 17. The cable 14 is suspended by a short cord 15, connected to the side wings 10 in 95 order that the same will deliver freely and not become entangled. The front portion of the keel 1 is upcurved and side ribs 19 extend forwardly and the parts are connected together, forming the stem of the 100 machine. Lateral wings 20-20 extend outwardly and join the side wings 10-10, as clearly appears in Fig. I. Windows 21 are disposed on this forward portion so that the pilot can look down without encountering the strong air current. This curved 105

portion secures the delivery of the air current against the side wings and insures that they will be spread when the machine is in flight.

- 5 The rudder lever 22 is connected by universal joint 25 to the front point or stem of the machine, and carries a horizontal blade 23, above which is disposed a longitudinal vertical blade 24. A cross arm 26
 10 affords a handle for the pilot to manipulate this rudder. It will be seen that he can tilt the rudder up or down, or laterally, as he chooses, and thus has complete and perfect control of the flying machine, both as
 15 to its altitude and as to its lateral movement. It is also clear that he is enabled to control the side wings 10' by means of the body lever 17. By leaning back against the lever and bringing both wings down, a considerable resistance can be offered to the
 20 progress of the machine and insures a reduction of speed at any time that it may be desired.

A horizontal rudder 27 is pivoted to the
 25 rear of the machine and is controlled by a forwardly-extending lever 28, which is connected to the cable 29, 30, which is disposed over suitable pulleys 29', 29', 29', 30' on the frame of the main body of the machine. A
 30 segmental lock 31 is connected to the cable 29, 30, so that the rudder 27 can be set at any angle desired, or the same can be very readily manipulated, as desired.

The masts 32, 33 at front and rear of the
 35 machine carry the upper frame structure, the various members of which are hinged together, there being upper frames 35, 35 and lower frames 36, 36, see Figs. I and III, which are collapsible on diagonal lines.
 40 The parts are supported by suitable longitudinal top bars 34, which are guided by the masts 32, 33, the bars 34 being adjustable by means of the cables 34^a, 34^a, which are disposed over the guiding pulley 34^b on
 45 the front mast 32. By manipulating these cables, the frames 35 and 36 can be raised. The upper frames 35 are covered by canvas 37, 37, and the lower frames 36 are covered by canvas 38, 38. Side wings 39 are hinged
 50 at each side of this collapsible structure and are disposed with stops 39' so that when the machine is in use they point outwardly and upwardly, see dotted lines in Fig. III, and greatly increase the stability of the machine. A propeller 40, which is driven by
 55 a suitable gasoline engine 41, or other suitable power, here indicated in conventional manner, is suitably disposed about midway of the main frame of the machine, see
 60 particularly Figs. II and III. The blades of the propeller are broad, their outer ends being defined by arcs of a circle from the center of rotation thereof. The combined area of the blades is coextensive with the

circle. Windows 42' are provided in the 65 lower side canvas 42 for the convenience of passengers that may be occupying the machine.

From this description, it will be seen that my improved flying machine can be operated either as a bi-plane or as a monoplane. When the upper structure is collapsed, the structure is substantially a monoplane. When the structure is elevated, it is a bi-plane with an especially effective 75 structure for increasing the stability of the machine.

I have described my improved flying machine in the form preferred by me. I desire to state, however, that much of the 80 structure is shown in a conventional way, and that many modifications will readily occur to those skilled in the art to which this invention relates.

I desire to claim the structure specifically, 85 as shown, and also broadly as defined in the appended claims.

Having thus described my invention, what I claim as new and desire to secure by Letters Patent is:

1. In a flying machine, the combination of a suitable keel; a suitable motor and propeller; a box-like body structure disposed above the keel with suitable canvas sides; diagonal horizontal transverse braces across the same; planes on said braces beyond the said body; collapsible wings hinged to the said planes on diagonal lines at each side converging toward the rear; a collapsible box-like balancing structure above the said main body; wings hinged at each side of said collapsible balancing structure with stops disposed to permit said wings to project outwardly and upwardly; suitable masts for guiding and supporting said collapsible structure; means for manipulating and adjusting said collapsible structure; forwardly-extending braces connected to the upwardly deflected front end of said keel to form a stem structure; a rudder with a horizontal plane and a longitudinal vertical plane connected by a universal joint to the said stem structure; a pilot seat; a handle to the said rudder extending rearwardly to the pilot seat; a back lever disposed back of the said pilot seat; connections therefrom to the lateral wings of the main planes; pivoted carrying wheels on suitable standards beneath the said machine; connections therefrom to the rudder whereby the said wheels will be deflected in the manipulation of the rudder to facilitate steering the machine in starting and alighting; and a horizontal rudder hinged to the rear of the machine with suitable cable connections for manipulating and adjusting the same, all coacting substantially as described and for the purpose specified.

2. In a flying machine, the combination of a suitable keel; a suitable motor and propeller; a box-like body structure disposed above the keel with suitable canvas sides; 5 diagonal horizontal transverse braces across the same; planes on said braces beyond the said body; collapsible wings hinged to the said planes on diagonal lines at each side converging toward the rear; forwardly-extending braces connected to the upwardly deflected front end of said keel to form a stem structure; a rudder with a horizontal plane and a longitudinal vertical plane connected by a universal joint to the said stem structure; a pilot seat; a handle to the said rudder extending rearwardly to the pilot seat; a back lever disposed back of the said pilot seat; connections therefrom to the lateral wings of the main planes; pivoted 10 carrying wheels on suitable standards beneath the said machine; connections therefrom to the rudder whereby the said wheels will be deflected in the manipulation of the rudder to facilitate steering the machine in starting and alighting; and a horizontal rudder hinged to the rear of the machine with suitable cable connections for manipulating and adjusting the same, all coacting substantially as described and for the purpose specified.
3. In a flying machine, the combination of a suitable keel; a suitable motor and propeller; a box-like body structure disposed above the keel with suitable canvas sides; 15 diagonal horizontal transverse braces across the same; planes on said braces beyond the said body; collapsible wings hinged to the said planes on diagonal lines at each side converging toward the rear; forwardly-extending braces connected to the upwardly deflected front end of said keel to form a stem structure; a rudder with a horizontal plane and a longitudinal vertical plane connected by a universal joint to the said stem structure; a pilot seat; a handle to the said rudder extending rearwardly to the pilot seat; a back lever disposed back of the said pilot seat; connections therefrom to the lateral wings of the main planes; and carrying 20 wheels on suitable standards beneath the said machine, all coacting substantially as described and for the purpose specified.
4. In a flying machine, the combination of a suitable keel; a suitable motor and propeller; a box-like body structure disposed above the keel with suitable canvas sides; 25 diagonal horizontal transverse braces across the same; planes on said braces beyond the said body; forwardly-extending braces connected to the upwardly deflected front end of said keel to form a stem structure; a rudder with a horizontal plane and a longitudinal vertical plane connected by a universal joint to the said stem structure; a pilot seat; a handle to the said rudder extending rearwardly to the pilot seat; a back lever disposed back of the said pilot seat; connections therefrom to the lateral wings of the main planes; pivoted carrying 30 wheels on suitable standards beneath the said machine; connections therefrom to the rudder whereby the said wheels will be deflected in the manipulation of the rudder to facilitate steering the machine in starting and alighting; and a horizontal rudder hinged to the rear of the machine with suitable cable connections for manipulating and adjusting the same, all coacting substantially as described and for the purpose specified.
5. In a flying machine, the combination of a suitable keel; a suitable motor and propeller; a box-like body structure disposed above the keel with suitable canvas sides; 35 diagonal horizontal transverse braces across the same; planes on said braces beyond the said body; collapsible wings hinged to the said planes on diagonal lines at each side converging toward the rear; forwardly-extending braces connected to the upwardly deflected front end of said keel to form a stem structure; a rudder with a horizontal plane and a longitudinal vertical plane connected by a universal joint to the said stem structure; a pilot seat; a handle to the said rudder extending rearwardly to the pilot seat; a back lever disposed back of the said pilot seat; connections therefrom to the lateral wings of the main planes; and carrying 40 wheels on suitable standards beneath the said machine, all coacting substantially as described and for the purpose specified.
6. In a flying machine, the combination of a suitable keel; a suitable motor and propeller; a box-like body structure disposed above the keel with suitable canvas sides; 45 diagonal horizontal transverse braces across the same; planes on said braces beyond the said body; collapsible wings hinged to the said planes on diagonal lines at each side converging toward the rear; a collapsible box-like balancing structure above the said main body; wings hinged at each side of the said balancing structure with stops disposed to permit said wings to project outwardly and upwardly; suitable masts for guiding and supporting said collapsible structure; means for manipulating and adjusting said collapsible structure; forwardly-extending braces connected to the upwardly deflected front end of said keel to form a stem structure; a rudder connected by a universal joint to the said stem structure; a pilot seat; a handle to the said rudder extending rearwardly to the pilot seat; a back lever disposed back of the pilot seat; connections therefrom to the lateral wings of the main planes; pivoted carrying 50 wheels on suitable standards beneath the said machine; connections therefrom to the rudder whereby the said wheels will be deflected in the manipulation of the rudder to facilitate steering the machine in starting and alighting; and a horizontal rudder hinged to the rear of the machine with suitable cable connections for manipulating and adjusting the same, all coacting substantially as described and for the purpose specified.

flected in the manipulation of the rudder to facilitate steering the machine in starting and alighting; and a horizontal rudder hinged to the rear of the machine with suitable cable connections for manipulating and adjusting the same, all coacting substantially as described and for the purpose specified.

7. In a flying machine, the combination of a suitable keel; a suitable motor and propeller; a box-like body structure disposed above the keel with suitable canvas sides; diagonal horizontal transverse braces across the same; planes on said braces beyond the 10 said body; collapsible wings hinged to the said planes on diagonal lines at each side converging toward the rear; forwardly-extending braces connected to the upwardly deflected front end of said keel to form a 15 stem structure; a rudder connected by a universal joint to the said stem structure; a pilot seat; a handle to the said rudder extending rearwardly to the pilot seat; a back lever disposed back of the said pilot seat; 20 connections therefrom to the lateral wings of the main planes; pivoted carrying wheels on suitable standards beneath the said machine; connections therefrom to the rudder whereby the said wheels will be deflected in 25 the manipulation of the rudder to facilitate steering the machine in starting and alighting; and a horizontal rudder hinged to the rear of the machine with suitable cable connections for manipulating and adjusting the 30 same, all coacting substantially as described and for the purpose specified.

8. In a flying machine, the combination of a suitable keel; a suitable motor and propeller; a box-like body structure disposed 40 above the keel with suitable canvas sides; diagonal horizontal transverse braces across the same; planes on said braces beyond the said body; collapsible wings hinged to the said planes on diagonal lines at each side 45 converging toward the rear; forwardly-extending braces connected to the upwardly deflected front end of said keel to form a stem structure; a rudder connected by a universal joint to the said stem structure; a 50 pilot seat; a handle to the said rudder extending rearwardly to the pilot seat; connections therefrom to the lateral wings of the main planes; carrying wheels on suitable standards beneath the said machine; 55 and a horizontal rudder hinged to the rear of the machine with suitable cable connections for manipulating and adjusting the same, all coacting substantially as described and for the purpose specified.

60 9. In a flying machine, the combination of a suitable keel; a suitable motor and propeller; a box-like body structure disposed above the keel with suitable canvas sides; diagonal horizontal transverse braces across

the same; planes on said braces beyond the 65 said body; forwardly extending braces connected to the upwardly deflected front end of said keel to form a stem structure; a rudder connected by a universal joint to the said stem structure; a pilot seat; a handle 70 to the said rudder extending rearwardly to the pilot seat; carrying wheels on suitable standards beneath the said machine; and a horizontal rudder hinged to the rear of the machine with suitable cable connections for 75 manipulating and adjusting the same, all coacting substantially as described and for the purpose specified.

10. In a flying machine, the combination of a suitable keel; a suitable motor and propeller; a box-like body structure disposed above the keel with suitable canvas sides; diagonal horizontal transverse braces across the same; planes on said braces beyond the 80 said body; collapsible wings hinged to the 85 said planes on diagonal lines at each side converging toward the rear; forwardly-extending braces connected to the upwardly deflected front end of said keel to form a stem structure; a rudder connected by a universal joint to the said stem structure; a pilot seat; a handle to the said rudder extending rearwardly to the pilot seat; a back lever disposed back of the said pilot seat; 90 connections therefrom to the lateral wings of the main planes; and carrying wheels on suitable standards beneath the said machine, all coacting substantially as described and for the purpose specified.

11. In a heavier than air flying machine, the combination of a frame with supporting planes therefor; a suitable motor and propeller; laterally-disposed adjustable wings pivoted to the said frame in oblique relation to the mid-line thereof; suitable cable connections for said adjustable wings to the structure; means for manipulating and adjusted to be operated by the body of the pilot; a forwardly-disposed rudder with a rearwardly-projecting lever; a handle disposed in front of the pilot; and a universal joint for suspending the rudder whereby it may be manipulated in all directions, as specified.

12. In a flying machine, the combination of a main body with lateral planes; a suitable motor and propeller; a collapsible box-like balancing structure above said main body; wings hinged at each side of said collapsible balancing structure with stops disposed to permit said wings to project outwardly and upwardly; suitable masts for guiding and supporting said collapsible structure; means for manipulating and adjusting said collapsible structure; and suitable rudder means for steering and controlling the same, as specified.

13. In a flying machine, the combination

of a main body with lateral planes; a suitable motor and propeller; a balancing structure above the said main body; wings hinged at each side of said balancing structure with stops disposed to permit said wings to project outwardly and upwardly; and suitable rudder means for steering and controlling the same, as specified.

In witness whereof, I have hereunto set my hand and seal in the presence of two witnesses.
